GARMENT HANGER

Harry M. Simmons and Henry C. Ruen, Detroit,
Mich., assignors to Cleaners Hanger Company,
Detroit, Mich., a corporation of Michigan

Application April 21, 1937, Serial No. 138,157

14 Claims. (Cl. 223—87)

This invention relates to garment hangers and particularly garment hangers comprising a garment support formed of stiff paper or the like and a wire hanger member.

It is desirable to form a garment support by bending a blank of relatively stiff paper to an arched shape so as to produce a pair of downwardly divergent garment seats connecting spaced front and rear walls, such support being medially engageable, by a wire hanger member. Such supports, however, have heretofore required the use of quite stiff paper to avoid a collapse, under load, at each side of the hanger member, involving a medial flaring apart of the walls.

An object of the invention is to reinforce a garment support of the disclosed type by establishing between its spaced walls, a tie connection resisting the increased flare incident to collapse.

Other objects are to establish such a tie connection substantially midway between the ends of the garment support, and to form such connection as an integral projection from one of the walls.

Another object is to form one of said walls with a tongue integrally projecting from the lower edge of such wall, and to employ such tongue as a tie connection between the walls.

A further object is to utilize a wire hanger member engaging one of said walls to secure to the latter a tie member integrally projecting from the other wall.

A further object is to utilize a wire hanger member to interconnect overlapped portions of the wall engaged by the hanger, whereby it is feasible to form the garment support from a flat blank of sheet material.

A further object is to utilize a portion of the wire hanger as a strut tending to maintain a desired minimum spacing of the walls.

These and various other objects are attained by the construction hereinafter described and illustrated in the accompanying drawing, wherein:

Fig. 1 is a top plan view of the improved garment hanger.

Fig. 2 is a rear elevational view of the same.

Fig. 3 is a vertical section view, taken on the line 3—3 of Fig. 2.

Fig. 4 is a view of the blank from which the garment supporting member is fashioned.

In these views, the reference character 1 designates a flat blank of stiff paper, laterally elongated and symmetrically shaped with respect to its vertical center line. The ends of the blank

are preferably rounded, its top and bottom edges converging in proximity to said ends. The blank is formed at its top with a notch 2 of approximate U-shape, downwardly extending along the vertical median, and a tongue 3 projects downwardly from the blank, also along such median. The notch 2 is productive of a pair of flaps 4, extending from said notch to the blank extremities, and at the juncture of each such flap with the body of the blank, the latter is formed with two score lines 5 extending, at a gradual divergence to the corresponding end of the blank. The flaps 4 are each formed at their adjacent ends with an aperture 6, so located that upon folding the blank upon the score lines 5, so as to overlap the adjacent ends of the flaps, said apertures are brought into relative registration. In the lower end portion of the tongue 3 there is formed an aperture 7, the purpose of which will presently appear.

Upon folding the disclosed blank on the lines 5, so as to overlap the adjacent ends of the flaps 4, there results an arched garment support having elongated triangular garment seats 8, downwardly diverging from the vertical median of the hanger, the relative angular relation of said seats adapting them to the shoulders of a dress or other garment to be carried by the support. The flaps 4 form a rear wall of said support and the main body of the blank forms a front wall 9, said walls preferably flaring slightly apart as they extend downwardly, as best appears in Fig. 3.

Connected to the described garment support, midway of its length, is a wire hanger member comprising a hook 10 and a shank 11, the latter projecting above the support to carry the hook and having a return-bent and approximately U-shaped lower portion, forming a spring clip 12 for fastening the hanger member to the support. Preferably, this clip serves also the purpose of interconnecting the flaps 4, to maintain their proper overlapping relation and desired arch shape of the support. Thus the shank 11 passes through the registered apertures 6 and so maintains their registration, and furthermore the clip 12 snugly embraces the overlapped portions of the flaps (see Fig. 3), quite strongly resisting relative shifting thereof. At the apex of the support, the shank rises, through the restricted end portion of the notch 2, the edges thereof assisting in maintaining the proper medial relation of the shank to the garment support. The upturned portion of the clip 12 lies between the walls 9 and 4 and its upper or ter-

final part is bent, preferably in the form of a gradual curve, to interiorly abut the wall 9 at a point below the top thereof, as illustrated in Fig. 3. The tongue 3 is upwardly bent and terminally connected to the overlapped portions of the flaps 4, the connection being established preferably by extending the upturned portion of the clip through the aperture 7 of said tongue.

In use of the described garment hanger, the tongue 3 forms a tie connection between the lower medial portions of the walls 4 and 9 and, in resisting spreading of such walls, adds strongly to the load capacity of said support. The strut-forming upper end portion of the clip 12 also exercises a material reinforcing effect, in preventing collapse by undue yielding of the walls toward each other.

It is to be observed that the clip 12 exercises a triple function, in attaching the hanger member to the garment support, interconnecting the flaps 4 so as to hold the support to its proper arched form, and interconnecting said flaps to the tongue 3.

The described hanger lends itself to compact and relatively inexpensive delivery in "knocked down" form, it being preferred to deliver the flat blanks to be bent to proper shape and connected to the hanger members by the customer (usually a dry cleaner). The score lines render bending of the blanks a simple matter, and attachment of the preformed wire hangers also requires no special skill, mechanism, or tools.

A garment hanger using a paper member as the garment support is less likely than an all-metal hanger to soil a garment hung thereon, will readily carry an advertisement, and eliminates need of the paper jackets or covers, commonly applied to all-metal hangers.

It is to be noted that the tie connection established by the tongue 3 inclines downwardly quite sharply from the clip 12 to the lower edge of the front wall of the support, permitting said tongue to transmit a proportion of load stresses from the wall 9 directly to the clip. This is quite desirable, since in the absence of such a tie connection, the load stresses set up in both walls must be carried to the wire hanger member through the wall 4, thus stressing the latter unduly as compared to the wall 9.

An economical feature of the described garment support lies in giving the mid portions of the upper and lower edges of the blank 1 the same contour. Thus it will be seen that the tongue 3 corresponds in size and shape to the notch 2, so that in shearing out the blanks from a sheet of stock the tongue 3 of one is struck out of the notch 2 of another, the upper and lower edges of adjacently formed blanks also corresponding for a considerable portion of their length. The amount of waste incident to formation of the blanks is thus minimized.

Employment of the tie connection 3 and derivation of a strut function from the clip 12, render the strength and load capacity of the described hanger at least three times greater than would otherwise prevail.

The invention is presented as including all such modifications and changes as come within the scope of the following claims.

70 What we claim is:

1. A garment hanger comprising a garment support providing a pair of garment seats, downwardly diverging from the mid portion to the ends of such support, and arched to form such seats and to form front and rear walls integrally

connected by the seats, a tongue integrally projecting from one of said walls, and a hanger member secured to the support and rising therefrom, substantially between the seats, and establishing a tie connection between the other wall 5 and said tongue.

2. A garment hanger comprising a garment support providing a pair of garment seats downwardly diverging from the mid portion to the ends of the support, and arched to form such 10 seats and to form front and rear walls integrally connected by the seats, a hanger member secured to the support and rising therefrom substantially between the seats, and a tie connection between said walls attached to one thereof by the hanger 15 member.

3. A garment hanger as set forth in claim 2, the hanger member being formed of wire and its lower portion forming a clip embracing one of said walls, said tie connection being secured 20 to such clip.

4. A garment hanger comprising a garment support formed from a blank of stiff paper, providing a pair of garment seats downwardly diverging from the mid portion to the ends of such 25 support, and arched to form such seats and to form front and rear walls integrally connected by the seats, and a hanger member secured to one of said walls and rising therefrom substantially between the seats, said hanger member 30 forming a strut between the walls, upwardly extending from the lower portion of the wall to which the hanger is secured and freely engaging the upper portion of the other wall.

5. A garment hanger comprising a garment 35 support formed from a blank of stiff sheet material and providing a pair of garment seats, downwardly diverging from the mid portion to the ends of such support, and arched to form such seats and to form front and rear walls integrally connected by the seats, one of said walls 40 primarily comprising a pair of flaps formed on said blank at opposite sides of its mid portion, a member interconnecting the flaps to maintain the arched form of the garment support, and a 45 tie connection between said walls attached by said member to the wall formed by the flaps.

6. A garment hanger as set forth in claim 5, said member being formed of wire and extending above the garment support to carry such 50 support.

7. A blank for garment support purposes, formed of stiff sheet material and having an opening extending from its margin toward its center, producing a pair of similar flaps, and 55 having a plurality of score lines extending in a gradually convergent relation toward the inner end portion of such opening from each end of the blank to facilitate folding the blank to an arched form and to provide a pair of garment 60 seats increasing in area as they extend from each other.

8. A blank for garment support purposes, formed of stiff sheet material and having a notch 65 extending from its margin toward its center producing a pair of similar flaps, adapted to be bent along divergent lines to impart to the blank an arched form and to jointly form a wall opposed to a wall formed by the remaining portion of the 70 blank, the blank having a tongue projecting from its margin at a point opposite to said notch and substantially conforming in proportions and shape to the notch, whereby such tongue of one blank may be struck out of the notch of another, 75

- the tongue serving in the garment support as a tie connection between said walls.
9. A garment hanger comprising a garment support fashioned from sheet material to form an arch having opposed walls of different downward extent, a hanger member secured to the wall of lesser downward extent, and a tie connection extending downwardly, from the wall of lesser downward extent to the wall of greater downward extent.
10. A garment hanger as set forth in claim 9, said tie connection being attached at its upper end portion to the hanger member.
11. A garment hanger comprising a garment support fashioned from sheet material to form an arch having opposed, downwardly divergent walls, a wire hanger member secured to one of said walls and projecting upwardly from the support, and a tie member extending to the other 20 of said walls from said hanger member, and resisting increased divergency of the walls, said tie member inclining downwardly from the hanger member and being thereby adapted to transmit directly to the hanger member a portion of the 25 load stresses acting in the wall engaged by its lower end.
12. A garment hanger comprising a garment support fashioned from a single sheet of material and forming an arch having opposed walls, one 30 of said walls comprising portions overlapped substantially midway between the ends of such wall, and a tie member in the form of a tongue projecting from the lower edge of the other wall and secured to the overlapping portions of first-mentioned wall.
13. A garment hanger comprising a garment support providing a pair of garment seats downwardly diverging from the mid portion to the 5 ends of such support, and arched to form such seats and to form front and rear walls integrally connected by the seats, and a wire hanger member rising from the support substantially between the seats, the lower portion of such hanger member 10 forming a clip extended under and embracing one of said walls, said clip having an upwardly projecting portion between the walls terminally bent to form a strut engaging both walls and maintaining their spaced relation.
14. A garment hanger comprising a garment support formed from a blank of stiff sheet material and providing a pair of garment seats, downwardly diverging from the mid portion to the 20 ends of such support, and arched to form such seats and to form front and rear walls integrally connected by the seats, one of said walls primarily comprising a pair of flaps formed on said blank at opposite sides of its mid portion, a tongue integrally projecting from the other wall, 25 and a hanger member secured to the support and rising therefrom substantially between said seats, said flaps being interconnected by said hanger member and said tongue being secured to the hanger member, whereby the tongue forms a tie 30 connection between the walls.
